UNITED STATES PATENT OFFICE

AUGUSTUS F. THOMPSON, OF HUNTINGTON, WEST VIRGINIA

RADIANT GAS HEATER

Application filed May 21, 1928. Serial No. 279,288.

The object of this invention is to provide a cabinet or console for a radiant gas-heater that will give to the heater the appearance of an ornamental piece of furniture and which at the same time will increase the heating capacity of the stove, as more fully hereinafter set forth.

In the drawing—

Fig. 1 is a front elevation of the apparatus 10 with one of the doors open;

Fig. 2 is a vertical sectional view on the line 2—2 of Fig. 4;

Fig. 3 is a perspective view of one of the doors;

15 Fig. 4 is a vertical sectional view on the line 4—4 of Fig. 2;

Fig. 5 is a horizontal sectional view on the line 5—5 of Fig. 4, showing one of the doors open and the other door closed.

20 Referring to the annexed drawing by reference-characters, 10 designates a sheet-metal back-wall of a cabinet; 11, sheet-metal end-walls; 12, a sheet-metal front-wall; and 13, a removable sheet-metal top-wall or plate.

25 At the corners, the sheet-metal walls are rigidly connected together by radial bolts 14 which extend through the bent, overlapped ends of the walls and through a vertical bar 15 lying against the inner overlap, these bolts 30 being rigidly fastened at their outer ends to a leg 16 which is hollow and extends the full height of the cabinet, the heads of the bolts 14 being rigidly connected to the inner faces of the hollow legs. The hollow legs are semi-

35 circular in form where they contact with the cabinet, so as to embrace the bent, overlapped edges of the cabinet. When the nuts on the bolts 14 are tightened, the vertical edges of the hollow open legs 16 are drawn tightly 40 against the faces of the adjacent walls, thus forming a substantial corner structure. The vertical strip 15 adds stiffness to the corner joint. The lower parts of the legs are circular in cross-section. The upper, semi-circular ends of the legs extend up under the

45 depending flanges 18 formed on the edges of the top-plate 13. The rear and end-walls are provided at their upper edges with inwardly-extending flanges 19 to give rigidity to the 50 cabinet, and, for the same reason, these walls

are inwardly flanged at 20 at their lower edges. The entire bottom of the cabinet is open. To give additional stiffness to the cabinet-casing, I prefer using sheet-metal angle-irons 21 lying in a recess between the 55 side-walls and end-walls and the depending flanges 18. The top-plate 13 is desirably made removable, and, by reason of this fact and the further fact that of using the bolts 14 at the corners, the whole structure is susceptible of being shipped in knockdown condition if that be desirable, or the legs alone 60 may be removed from the cabinet for shipping purposes.

Within the cabinet is mounted a burner, 65 preferably of the type illustrated in my former Patents 1,563,050, dated November 24, 1925, and 1,637,014, dated July 26, 1927, gas being supplied to the burner through the medium of an adjustable gas-jetting device 70 22 supported on a transverse plate 23, to which plate is also riveted one end of the burner. The burner is mounted within the cabinet, at a distance from the front-wall thereof, and on the top, distributing-tube 24 75 of the burner is mounted, in the usual manner, the clay radiants 25, of any suitable design. I have shown six of these radiants in the present instance, but more or less may be used. The lower ends of the radiants rest 80 on the distributing-tube 24, as usual, and their top edges are held in alinement by means of a channel-iron 26. By slightly lifting the radiants and swinging their lower-ends outwardly, they may be removed separately. 85

Arranged in front of the series of radiants are four inclined light-reflecting and heat-reflecting walls 27, their outer faces being polished. These walls incline outwardly so as to present bevelled or inclined surfaces at 90 the front to thus tend to reflect the light and the heat outwardly through the opening in the front-wall. The lower reflecting-wall 27 extends from the mixing-tube to the front-wall 12, where it is riveted to the inwardly-extending flange 28, the inner edge of this reflecting-wall 27 resting on little lugs 29 formed on the front-face of the mixing-tube. The top-wall 27 extends from the aforesaid channel-iron 26 to the flange 28, to which 95 100

it is riveted. The end-walls 27 are rigidly attached to vertical sheet-metal posts 30 built into the cabinet-frame and are thence extended inwardly past the burner and riveted to a vertical wall 31 built into the frame of the cabinet and lying just back of the radiants.

The opposite ends of the wall 31 are connected to the back-wall 10 by vertical walls 32 which, together with a top-plate 33 and a bottom-plate 34, form a hot-air chamber immediately back of the radiants. The front or heat wall 31 terminates short of the bottom-plate 34 so as to leave an opening for hot air to circulate to a certain extent. Up through the hot-air chamber 35 (formed by walls 31, 32, 33 and 34) extends a series of open-ended tubes 36. The lower ends of tubes 36 are open so that heated air may rise through the tubes and pass up into the top hot-air chamber 37 formed in the upper part of the cabinet. The heated air from chamber 37 escapes out into the room through a multiplicity of openings 38 formed in the front-wall 12 above the door-opening therein. The heated air is therefore caused to pass up through heating-tubes 36 into the distributing-chamber 37 and thence out through the holes 38. Of course, additional heat will be radiated and reflected out through the front opening in the cabinet, the reflection of the heat and light being assisted by means of the polished inclined walls 27 surrounding the radiants.

Over the top of the radiants and the channel-iron 23 is a closed chamber 39 which is connected to a flue 40 which extends horizontally backward through the back-wall 10. This chamber 39 extends the length of the row of radiants and is open along its lower edge to receive the products of combustion arising from the radiants, and these products are passed out through flue 40 to a suitable connection which will deliver them into a chimney if it be desired to connect the apparatus with a chimney for the discharge of the products of combustion. The hot-plate 31 serves to heat the air of chamber 35 and the flue-chambers 39-40 serve to heat the air passing through the upper hot-air chamber of the cabinet. It will be observed that the hot-products chamber 39 is closed at its front and rear walls and at its ends and that it extends at least the length of the row of radiants and, further, that it is located approximately midway between the front and rear walls of the cabinet, its rear wall being connected to the rear wall of the cabinet by a smoke-flue 40. With this arrangement, it will be seen that the maximum of efficiency is obtained in heating the air going up through the tubes 36 and up through the flues formed at the ends of the air-chamber 35 as the air passes upwardly and forwardly to

the escape-openings 38 in the front wall of the cabinet.

I provide the cabinet with two sliding doors 41, each constructed of sheet metal. These doors are each adapted to slide in a sheet-metal channel 42 supported in the cabinet on horizontal flanges 43 formed on the upper edges of the plates 23. When these doors are pulled outwardly as far as they can come, they are adapted to swing inwardly upon the cabinet and meet in the middle of the door-opening and thus close the opening, thereby obscuring the radiants as well as the reflecting-surfaces 27 from view and giving to the apparatus the appearance of an ornamental piece of furniture of the type of a console. The doors when closed fit within the marginal flange 28 and rest therein, and when slid inwardly as far as they will go in the channels 42 their outer edges are flush with the front-wall 12. To give stiffness to the doors, their edges are flanged, and, in order to prevent them from being pulled out of the cabinet when they are open, I provide each door with a vertical flange 43 near its rear edge, which, when the door is drawn outwardly to the limit, will strike against an abutment-plate 44 fastened to the adjacent post 30, thus preventing the door being pulled entirely out of the channel 42, but permitting it to swing inwardly toward the face of the cabinet. The flange 43 resting against the projecting-edge of the plate 44 forms a sort of hinge, and, in order that this hinge action may take place, one wall of the channel at 45 is bent outwardly. The flanges at the outer edges of the doors are provided with inwardly-turned stop-lips 46 which, when the doors are closed, abut against the outer faces of the stop-flanges of plate 44 and arrest the doors in position with their front edges flush with the face of the front-wall.

What I claim as new is:

1. In a radiant gas heater, a cabinet, a burner and a row of radiants supported in the cabinet, a flue arrangement for conducting off the products of combustion from the radiants embodying a closed chamber spaced away from the front wall as well as the back wall of the cabinet and mounted in the upper part thereof and having its closed ends terminate short of the side walls of the cabinet, a smoke-flue connecting the rear wall of this chamber to the rear wall of the cabinet, a vertical plate at the back of the radiants at a distance from the back wall of the cabinet, the front wall of the cabinet at the top thereof being provided with hot-air escape-openings whereby air rising up in the space between the aforesaid vertical plate and the back wall of the cabinet will pass over and around the said chamber and flue before escaping through said front openings.

2. In a radiant gas heater, a cabinet, a burner and a series of radiants supported in

the cabinet, a flue arrangement for conducting off the products of combustion from the radiants embodying a closed chamber spaced away from the front wall as well as the back wall of the cabinet and mounted in the upper part thereof, a smoke-flue connecting the rear wall of this chamber to the rear wall of the cabinet, a vertical plate at the back of the radiants at a distance from the back wall of the cabinet, the front wall of the cabinet at the top thereof being provided with hot-air escape-openings whereby air rising up in the space between the aforesaid vertical plate and the back wall of the cabinet will pass over and around the said chamber and flue before escaping through said front openings, said space between the radiant-plate and the back wall being boxed in by vertical as well as horizontal walls and having air-flues vertically extending therethrough.

In testimony whereof I hereunto affix my signature.

AUGUSTUS F. THOMPSON.
